Primary Examiner—Catherine Tuttle(74) Attorney, Agent, or Firm—Fay, Sharpe, Fagan, Minnich & McKee, LLP(57) CLAIM

The ornamental design for a sportsball, as shown and described.

DESCRIPTION

FIG. 1 is a front elevational view of a sportsball showing our new design;

FIG. 2 is a right side elevational view thereof;

FIG. 3 is a rear elevational view thereof;

FIG. 4 is the left side elevational view thereof;

FIG. 5 is a top plan view thereof; and,

FIG. 6 is a bottom plan view thereof.

The portions shown in broken lines are for illustrative purposes only; and form no part of the claimed design.
